CLOSURE CAP FOR A CONTAINER

Daniel Goldstein, New York, N.Y., assignor to Schenley
Industries, Inc., New York, N.Y., a corporation of
Delaware

Application September 3, 1958, Serial No. 52,484

Term of patent 14 years

(Cl. D58—26)

FIG. 2.

FIG. 4.

FIG. 3.

Fig. 1 is a top plan view of a closure cap for a container, showing my new design;

Fig. 2 is a rear elevation of the cap.

Fig. 3 is a bottom plan view of the cap.

Fig. 4 is a side elevation of the cap, in inverted position.

The broken line showing of the container in Fig. 1 is for illustrative purposes only.

I claim:

The ornamental design for a closure cap for a container substantially as shown and described.
